LEROY M. LEWIS, OF MERION, PENNSYLVANIA.

FUSIBLE LINK.

1,244,106.

Specification of Letters Patent. Patented Oct. 23, 1917.

Application filed July 21, 1916. Serial No. 110,449.

To all whom it may concern:

Be it known that I, LEROY M. LEWIS, a citizen of the United States, and a resident of Merion, county of Montgomery, and State 5 of Pennsylvania, have invented certain new and useful Improvements in Fusible Links, of which the following is a specification, reference being had to the accompanying drawing.

10 My invention relates to fusible links of the sort more especially intended for use with automatic sprinkler heads for fire extinguishing apparatus and other devices wherein it is desired to maintain certain elements in positive relation until the temperature in the vicinity of the apparatus reaches a point sufficient to melt a fusible material normally uniting the parts of the link in assembled relation to permit the separation 15 thereof and consequent release of the elements of the mechanism with which the link is arranged to coöperate.

Among the principal objects of my invention are to provide a fusible link of this 25 character which shall be positive and efficient in operation, and in which a positive and substantially instantaneous separation of the members of the link will occur when the temperature in the vicinity of the link 30 is raised sufficiently to cause the melting of the fusible material which normally serves to secure the members in assembled relation.

Further objects of my invention are to 35 provide a fusible link having the foregoing characteristics, which shall be of great strength, which can be readily and cheaply constructed, which shall be so designed as to minimize the strain upon the fusible material which serves to normally unite the 40 members of the link, and in which relative movement or "creeping" of the members will not occur even though the link be kept under maximum tension for long periods of time as when used in connection with automatic 45 sprinkler heads for fire extinguishing systems.

My invention further includes all of the various other novel objects and features of construction and arrangement hereinafter 50 more definitely specified and described.

In the accompanying drawing is illustrated a fusible link constructed in accordance with a preferred embodiment of my invention, Figure 1 being a side elevation of the link in operative position upon fragmentary portions of the lever arms of an

automatic sprinkler head; Fig. 2 a central vertical section of the link removed from the arms; Figs. 3, 4 and 5, respectively, side elevations of the several members composing 60 the link and separated from each other, and Figs. 6, 7 and 8, respectively, front elevations of the members shown in Figs. 3, 4 and 5.

The form of the invention illustrated in 65 the drawing comprises three separate members adapted to suitably coact with each other when assembled to form the completed link, the several members being normally maintained in assembled relation by 70 suitable fusible material or solder disposed between their adjacent surfaces.

More specifically, each link comprises an intermediate member A and exterior members B and C each having a body preferably 75 formed from suitable sheet metal or the like and provided with suitably disposed projections or indentations arranged for engagement with corresponding indentations or projections of an adjacent member in the 80 manner hereinafter described. Preferably the intermediate member A may comprise a flat substantially oblong body 1 provided with oppositely disposed projections 3 and 4, 4, the projection 3 extending outwardly 85 from one side of the body and centrally thereof, and the projections 4, 4 extending outwardly from the other side of the body and on either side of projection 3, the combined width of all of the projections being 90 preferably equal to that of the body portion and each projection being substantially one-third of the width thereof. The projections may be struck from the body or otherwise formed thereon in any desired shape or out-

line but may each preferably comprise two distinct sides forming substantially a right angle with each other so that the projections in member A, when the latter is viewed as in Fig. 4, will together substantially outline a square having one of its diagonals lying in a plane parallel to the body of the member and equidistant from its surfaces. The projections are preferably located in alignment transversely of the member and somewhat nearer one end of the body than

the other and a suitable aperture 6 provided adjacent the extremity of the longer end thereof, to permit the passage through the body of an arm of the sprinkler head, or the 110 like, with which the link is intended to co-operate.

The members B and C are each provided with one or more indentations or depressions suitable for the reception of the projections on the intermediate member A hereinbefore described. In the preferred form of the invention the member B comprises a single indentation or depression 9 located preferably somewhat nearer one end of the member than the other and equally distant from the lateral edges thereof, the width of the indentation being preferably substantially one-third of that of the member, and hence substantially equal to the width of the projection 3 of member A. Similarly member C is preferably provided with two suitable indentations or depressions 12, 12 corresponding to projections 4, 4 on member A and located one adjacent each lateral edge of the member, each indentation being substantially equal in width to one-third of the width of the body 13 of the member and both being formed in the same surface of the body and extending in the same direction therefrom.

While the indentations or depressions in members B and C may be formed in any suitable manner to adapt them for engagement with the surfaces of the corresponding projections on member A when the members are placed in assembled relation without any fusible material between the adjacent surfaces thereof, yet it is preferable, especially when the members are formed from sheet metal or the like, to form each indentation by means of suitable dies adapted to bend out a portion of the metal from the body of the member into a sort of V having an angle of substantially 90 degrees between its interior adjacent faces when the projections on member A are formed as hereinbefore described, or other suitable angle corresponding to the angle formed by the sides of the projections in case the angles of these projections be varied from those employed in the preferred embodiment of the invention, each indentation being of a suitable size to fit over and contact with the outer surface of its corresponding projection on member A when the members are brought together into assembled relation without any fusible metal between their adjacent faces. In practice, it is preferable to form the projections very slightly narrower than the corresponding indentations in order that a slight clearance may be provided between the edges of the projections and the adjacent portions of members B and C when the link is assembled in order to permit the ready separation of the parts of the link in operation.

The bodies of members B and C are each provided with suitable apertures 14, 14 disposed adjacent that end of each body farthest from the indentation or indentations therein, these apertures being arranged

to come into substantial alignment with each other when the link is assembled to afford means whereby the link may be engaged by one of the arms of the sprinkler head, or the like, to which it is attached when in use as shown in Fig. 1.

The various members of the link, having been formed as hereinbefore described, may be assembled in the position shown in Figs. 1 and 2; that is with the projection 3 engaging in indentation 9 and projections 4, 4 engaging in indentations 12, 12, suitable fusible metal 15 being disposed between the adjacent faces of the members to normally unite them together as will be readily understood by those familiar with the art. In this position that end of member A having aperture 6 will extend beyond the adjacent ends of members B and C, and in a corresponding manner the ends of members B and C having apertures 14 will extend beyond the adjacent end of member A to permit the ready attachment of the link to the arms of the sprinkler head or to other apparatus with which it is intended to co-operate.

When the link is attached to a sprinkler head as shown in Fig. 1, so long as the temperature in the vicinity thereof remains below the fusing point of the material 15 the members of the link will remain in positive assembled relation, being held in that position by the fusible material between their adjacent faces. It will be evident that in their assembled position the several members of the link will each present a large surface for contact with the fusible material, and that the latter, moreover, will be relieved of a large part of the strain exerted by the arms of the sprinkler head by reason of the mutual engagement of the several projections and indentations with which the members of the link are provided so that, in fact, the duty of the fusible material is substantially reduced to that of merely holding the members together. In consequence, relative movement or creeping between the members is avoided even though the link may be kept under heavy strain for long periods of time provided that the temperature of the surrounding atmosphere remains below the fusing point of the fusible material. When the temperature in the vicinity of the link, however, rises to a point sufficient to melt the fusible material, the strain exerted by the lever arms or other devices to which the link is attached causes a relative longitudinal movement of the member A, and members B and C which, in turn, forces members B and C laterally outward as the struck-up portions 3 and 4, 4 of member A move longitudinally with respect to members B and C, thus moving both of the latter away from member A with a wedging action and resulting in a

positive and substantially instantaneous relative separation of all of the members to release the lever arms of the sprinkler head or other device to which the link may be attached.

It will be evident that a very slight relative longitudinal movement of the members will result in forcing the outer members B and C away from the intermediate member A for a relatively considerable distance so that the water issuing from the sprinkler head and striking the members of the link will not serve to prevent their positive separation by chilling the fusible material between their adjacent surfaces after it has once fused, but that, on the contrary, as soon as the fusible material melts sufficiently to permit any relative movement of the members, the complete and positive separation of all of them will be assured under any and all conditions.

Although I have illustrated my improved link in Fig. 1 in operative position upon fragmentary portions of the arms of a sprinkler head tending normally to separate under the pressure of the fluid within the sprinkler system, which tendency is normally resisted by the operation of the link, it will be further evident that my improved link is equally adapted for use in connection with mechanisms having parts normally tending to move toward each other instead of to separate, and that when used in connection with such mechanisms the link, while normally under longitudinal compression instead of tension, will serve equally well to maintain the movable parts to which it is attached in fixed relation until the fusing of the material 15 when the members of the link will positively and promptly separate to permit the parts to which they have been attached to move toward each other to effect the purposes of the device.

While I have herein illustrated and described a preferred embodiment of my invention with considerable particularity, I do not desire or intend to thereby limit myself specifically thereto, as it will be evident that various changes and modifications may be made in the details of construction and arrangement of the various parts, and the relative proportions thereof may be varied as desired, and that members having projections and corresponding indentations dif-

fering in number from those herein illustrated and described may be employed, without departing from the spirit and scope of the invention as defined in the appended claims.

Having thus described my invention I claim and desire to protect by Letters Patent of the United States:—

1. A fusible link comprising an intermediate member having a body and a single projection extending outwardly from one side thereof equidistant from the lateral edges of said body and a pair of projections extending outwardly from the other side thereof adjacent the lateral edges of said body, and a pair of exterior members, one of said members having a single indentation adapted to receive said first-mentioned projection and located equidistant from the lateral edges of said member and the other of said members having a pair of indentations adapted to receive said last-mentioned projections and located adjacent the lateral edges of said member, said indentations extending in a single direction from the planes of the bodies of their respective members.

2. A fusible link comprising an intermediate member having a body and alined projections extending outwardly therefrom, one of said projections extending from one side of said body and equidistant from the lateral edges thereof, and the other projections extending from the opposite side of said body adjacent the lateral edges thereof, and a pair of exterior members respectively indented in a single direction, one of said members having an indentation adapted to receive said first-mentioned projection and positioned equidistant from the lateral edges of said member, and the other of said members having a pair of indentations each adapted to receive one of said last-mentioned projections each positioned adjacent the lateral edges of said member, and fusible material between the adjacent surfaces of said members operative to maintain said members in operative relation.

In witness whereof I have hereunto set my hand this 19th day of July, A. D. 1916.

LEROY M. LEWIS.
